DIVER'S DRESS

William Scrimgeour, Washington, D. C., assignor
of one-eighth to Carter Maxwell Scrimgeour,
Washington, D. C.

Application July 1, 1932. Serial No. 620,477

12 Claims. (Cl. 61—70)

This invention relates to diving dress, and particularly to the helmet forming a part of such diving dress.

In diving dress, as now generally constructed, the breast plate of the helmet is relatively permanently attached to the neck opening of the diving suit by means of a flange and a retaining ring between which the edge of the neck opening is securely bolted, and the helmet proper is made

10 removable from the breast plate.

With such diving dress a diver, while waiting to descend, wears all of the dress except the helmet proper, which is unscrewed from the breast plate and removed, but the breast plate itself is 15 heavy and rigid and if the diver must wear his dress for any length of time before descending he is subjected to the weight and discomfort not only of the suit proper but of the breast plate and its attaching means.

20 One object of the present invention is to provide a diving helmet in which the helmet proper and the breast plate therefor are made as a unitary structure of relatively light gauge but strong sheet metal and to so connect the border or edge 25 of the neck opening of the suit with the breast plate that the helmet as a whole may be quickly and easily connected with the suit and disconnected therefrom, thus making possible the removal and replacement of the helmet proper and 30 breast plate as a unit, whereby the diver, while waiting to descend is relieved of the weight of the whole helmet structure but, due to the ease with which this helmet structure is fastened to the suit, may have the helmet quickly applied 35 so that he may be made ready for descent on short notice, as is requisite in diving operations.

Another object of the invention is to provide 40 an improvement in the means for and manner of introducing air into the helmet so that its velocity and the noise usually created by its introduction may be reduced.

A further object of the invention is to provide 45 for increasing the range of vision of the diver by the application to the helmet of observation glasses providing much larger sight openings or windows than is customary.

With these objects in view the invention contemplates a diving helmet including a helmet proper and a breast plate therefor preferably permanently connected, the breast plate being provided with a member adapted to receive the border or edge of the neck opening of the diving suit, complementary means being arranged for quickly clamping this edge in a fluid tight manner relatively to said member, and for as quickly

unclamping it so that the helmet may be easily and quickly removed.

The invention contemplates also a member assembled in connection with the air inlet for the helmet, formed of sound-deadening material 60 and provided with appropriately arranged baffles so that the air supplied under pressure to the helmet may be admitted to the helmet relatively silently and at lessened velocity.

The invention contemplates further the provision of large sight openings or windows for the helmet, including means for accomplishing the fluid tight mounting of the glasses of these windows.

In the accompanying drawings illustrating the 70 invention, in the several figures of which like parts are similarly designated,

Fig. 1 is a front elevation, with parts in section, illustrating a diving helmet constructed in accordance with the invention, certain parts of the 75 clamping means being omitted.

Fig. 2 is a side elevation of the helmet.

Fig. 3 is an enlarged fragmentary sectional elevation taken substantially centrally of Fig. 1.

Fig. 4 is a central fragmentary sectional view 80 of the helmet illustrating the air inlet arrangement.

Figs. 5 and 6 are a side and a front elevation, respectively, of the member of sound-deadening material associated with the air inlet.

The helmet comprises a helmet proper 1, of more or less conventional conformation, and a breast plate 2, these parts preferably being formed separately and provided with complementary sleeve portions 3 and 4, respectively, arranged in telescoping relation and secured fluid tight, preferably by welding.

The breast plate 2 is so shaped as to comfortably fit the shoulders and chest of a diver, as is customary, and the breast plate has rigidly mounted, preferably by welding around its perimeter, a channel member 5 of continuous form. This channel member is so formed or twisted that at the portions which extend over the shoulders of the diver its channel opens upwardly, whereas at the front and back its channel opens downwardly.

At substantially diametrically opposite points at the sides of the united parts 3 and 4 are fixed hinge lugs 6 to which are pivoted carrier members 7, and to each of these carrier members 7 is affixed, as by welding, a flexible element or cable 8, preferably of stranded form and of a length sufficient to extend from the front to the back of 110

the breast plate following the course of the channel member. At one of its ends each of these flexible elements or cables 8 passes into and has rigidly attached to it a socket piece 9 carrying 5 a pair of spaced jaws 10, and at its other end passes into and has rigidly attached to it a socket piece 11 provided with spaced ears 12 between which is pivotally mounted at 13 a lever 14 having pivoted to it at 15 a link 16 threaded and 10 provided with an adjusting nut 17 having a rounded bearing surface 18 for engagement with the complementally shaped bearing faces of the lugs 10. By this arrangement it will be seen that 15 similar means are provided at the front and back of the breast plate for joining the ends of the cables and for enabling them to be pulled together, the pivoted arrangement of the carrier members 7 permitting the cables 8 to move toward the channel member 5 as the cables are 20 tightened or tensioned by the linkages connecting their ends.

As illustrated in Figs. 1 and 2, the edge or border of the neck opening of the diving suit is 25 preferably so molded as to provide a relatively permanent bead 19 for engagement with the channel member 5 and with which the cables 3 so cooperate that when the linkages connecting the ends of the cables are tensioned or tightened 30 the bead 19 will be forced firmly into the channel member 5 to provide a fluid tight connection between the helmet and the suit.

It will be noted that the pivot 13 of each of the 35 levers 14 is so positioned that when the levers 14 are in closed position, as shown in Fig. 1, a line passing through the pivot 15 and the point of bearing of the nut 18 upon the jaws 10 (which is the line in which the pulling or tensioning stress upon the cable lies) will be inside of the pivot 13 and that, therefore, once the cables are 40 tightened by moving the levers 14 to their closed position, as described, any tendency of the cables to separate, as might be produced by pressure within the diving dress will cause the levers to be more firmly forced to closed position. In order, 45 however, that accidental fouling of the levers 14 may not cause them to move to open position, each lever may be provided at its end with a portion 20 rounded or otherwise appropriately shaped for snap engagement with a fixed spring 50 clip or retaining device 21.

Obviously, when the bead 19 has been clamped in the channel member 5, as described, the appropriate pressure of the cables 8 may be adjusted by means of the nuts 17 to provide the 55 desired fluid tight joint between the bead 19 and member 5. After this adjustment is made, the nuts 17 may be permitted to remain in their adjusted position, and the tensioning of the cables 8 to connect the helmet with the suit, and their release to disconnect the helmet from the suit, 60 may be accomplished solely by operation of the levers 14 at the front and back of the breast plate. Consequently, it will be apparent that the helmet may be very quickly and easily 65 connected with and disconnected from the suit, and the diver thus easily and quickly supplied with and relieved of the helmet.

The twisting of the channel member 5, as hereinbefore described, makes possible tensioning 70 of the cables 8 in the bead 19 to secure the edge of the neck opening in the channel member without danger of the cables slipping out of engagement therewith.

The members 7, in addition to serving as a 75 means for positioning the cables 8 and connecting

them with the helmet provide, upon their upper longitudinally curved surfaces, bearings for the customary shoulder straps which support the belt containing the waist weights.

As shown particularly in Fig. 3, the channel member 5, due to its twisted formation, stands away considerably from the breast plate at the front and back portions of the edge thereof, where it is welded to it, and in order that its connection with the breast plate at these portions may be strengthened and the appreciable offstanding shoulder formed by it protected, fairing pieces 22 (see Figs. 1, 2 and 3), are welded to the breast plate and to the offstanding edge portion of the channel member 5, thus producing a smooth curved surface between the channel member and the breast plate.

The helmet is provided with the usual telephone 23, and with a connection 24 through which the telephone cable is introduced in the 95 usual manner, and it is also provided with a chin valve 25 and air exhaust 26 of conventional form. The air inlet for the helmet, however, is of novel design and arrangement.

Instead of having the air introduced at the 100 lower back portion of the helmet, as is the usual practice, the air inlet arrangement of this invention provides that the air be introduced through an opening 27 in the top of the helmet, this opening lying within the confines of an 105 offstanding substantially U-shaped sheath 28 stream-lined from front to rear and welded to the helmet around its edges and provided with means 29 for connection with the customary air hose. Within the sheath 28 is arranged an air 110 inlet or lining member 30 formed of resilient or pliable sound-deadening material, preferably rubber, of substantially the same shape as the space defined by the sheath 28 and the adjacent portions of the helmet 1, but terminating short 115 of the opening 27. This air inlet member 30 is provided with opposed baffles 32 and 33 and with an opening 34 which latter registers with the air connection 29. The forward end of the air inlet member 30 is open, as indicated at 35, 120 so that the air passing through it may escape into the helmet through the opening 27. As the air under pressure enters the inlet member 30, the force of its current will be broken up by the baffles 33 and 32 and the hissing noise 125 commonly present in ordinary air admission tubes thus relieved. The relieving of this hissing noise is further accomplished by the sound-deadening properties of the material, preferably rubber, of which the air inlet member is constructed. 130

As will be apparent, particularly from an inspection of Figs. 5 and 6, the air inlet member 30 is flared laterally from bottom to top so that, although it also tapers vertically in this direction to conform to the stream-line of the sheath 28, 135 it is throughout its interior of substantially the same cross sectional area and thus offers no appreciable obstruction to the free passage of the air through it.

Heretofore diving helmets, so far as is known, 140 have been provided with sight openings or windows of rather small area due to the fact that they must be so constructed as to be easily opened and closed thus providing a means whereby the diver may breathe atmospheric air when not submerged and, in emergencies, making unnecessary removal of the helmet from the diving dress to relieve the diver, which removal is ordinarily accomplished with some difficulty, dependent upon the pressure within the dress. However, due to 145

the ease with which the helmet of this invention may be disconnected from the suit by means of the cable connecting device, it is possible to provide permanently sealed or fluid tight sight openings of much larger area than has heretofore been practicable. In accordance with this invention the helmet is supplied with two windows or sight openings, one of which, 36, extends fully from side to side across the front portion of the helmet 5 and the other of which, 37, is arranged at the upper front portion of the helmet in conventional position. Each of these sight openings is provided with a glass 38 so shaped, and molded to such curvature, as to fit the opening and the 10 curvature of the helmet. Each of the glasses 38 is mounted fluid-tight by means of a preferably U-shaped gasket 39 (see Fig. 3) extending around its periphery between a bearing plate 40 welded to the helmet around its respective sight opening 15 and a clamping rim 41 recessed to receive the glass and gasket and connected with the plate 40 by screws 42. As shown, the screws 42 pass completely through the plate 40, the thread of the screws being made so fine as to prevent entrance of water or escape of air. However, the 20 plate 40 may be of such thickness that the tapped holes for reception of the screws 42 need not extend completely therethrough, thus sealing the connection. 25

The sight openings may be provided with the usual spaced protecting bars, or they may be protected by heavy wire mesh 43, as shown, welded to the rims 41.

Due to the curved or arched formation of the 30 glasses 38, they are of sufficient strength to withstand surrounding water pressure, particularly when it is considered that they are simultaneously supported from within by air pressure within the helmet.

From the foregoing, it will be seen that the 35 invention provides a diving helmet having novel features which not only make it easier to apply to and disconnect from the suit than helmets of conventional type, but which embodies structural features tending to increase the comfort and security of the diver, particularly when submerged.

Various changes and modifications are considered to be within the spirit of the invention and 40 the scope of the following claims.

I claim:

1. A diving helmet having means for connecting it with the border of the neck opening of a diving suit, said means comprising a breast plate 55 having a peripheral portion adapted to receive the border of said neck opening, a flexible element arranged for engagement with said border and disposed in alignment with said peripheral portion, and means for tensioning said element upon said border to thereby produce a fluid-tight joint between said border and said breast plate.

2. A diving helmet having means for connecting it with the border of the neck opening of a diving suit, said means comprising a breast plate 65 having a channel member adapted to receive the border of said neck opening, a flexible element arranged for engagement with said border and disposed in alignment with said channel member, and means for tensioning said element upon said 70 border to thereby produce a fluid tight joint between said border and said channel member.

3. A diving helmet comprising a helmet proper and a breast plate, and means for connecting said helmet with the border of the neck opening 75 of a diving suit, said means comprising a channel

member carried by the breast plate and adapted to receive the border of said neck opening, a flexible cable arranged for engagement with said border in alignment with said channel member, and means for tensioning said cable to exert pressure upon said border and press same against said channel member to produce a fluid-tight joint between the helmet and suit. 80

4. A diving helmet, having a breast plate, and means for connecting said helmet to the border of the neck opening of a diving suit, said means including a channel member disposed adjacent to the edge of said breast plate and permanently attached thereto, a pair of similar flexible cables carried by said helmet and disposed for cooperative alignment with said channel member, said cables and channel member adapted to receive between them the border of said neck opening, and means for joining the ends of the respective cables and for tensioning same to apply pressure to said border and thereby provide a fluid tight joint between same and said channel member. 85

5. In a diving helmet, means carried thereby for connecting same fluid-tight to the border of the neck opening of a diving suit, said means including a breast plate having a channel member extending continuously around the periphery thereof and cables cooperating with said channel member and between which and said channel member said border is gripped, and means for tensioning and releasing said cables comprising means for joining the respective cable ends and including a linkage and a lever for operating same. 90

6. In a diving helmet having a breast plate the edge of which is of non-circular contour, means for connecting said helmet fluid-tight to the border of the neck opening of a diving suit, said means including a channel member carried 115 by and following the edge contour of said breast plate and adapted to receive said border, and a cable arranged to secure said border with relation to said channel member, said cable provided with means whereby it may be tightened 120 and released, the arrangement of said channel member relatively to said breast plate being such as to so present its channel that when said cable is tightened pressure will be applied to said border throughout its extent regardless of the non-circular contour of said channel member. 125

7. In apparatus of the type stated, a helmet, a breast plate secured thereto, a channel member secured to the periphery of said breast plate, said channel member being twisted to open upwardly at the shoulder portions of said breast plate and to open downwardly at the front and rear thereof, and flexible means adapted to be tightened into said channel member to clamp thereto the border edge of the neck opening of 130 a diver's suit. 135

8. The invention as set forth in claim 7, wherein said flexible means comprises a pair of cables having their intermediate portions pivotally connected to said breast plate adjacent the 140 shoulder portions thereof, and cooperating means on the adjacent ends of said cables at the front and rear of said breast plate for tensioning said cables.

9. The invention as set forth in claim 7, where- 145 in said flexible means comprise a pair of cables alined with said channel member and extending from front to rear of said breast plate around opposite sides thereof, cooperating tension means on adjacent ends of said cables at the 150

front and rear of said breast plate, and carrier members secured to the intermediate portions of the respective cables and pivotally supported on said breast plate.

- 5 10. The invention as set forth in claim 7, wherein said flexible means comprise a pair of cables alined with said channel member and extending from front to rear of said breast plate around opposite sides thereof, cooperating tension means on adjacent ends of said cables at the front and rear of said breast plate, and carrier members secured to the intermediate portions of the respective cables and pivotally supported on said breast plate, said carrier members 15 being turned upward at their outer edges, thereby to provide supporting surfaces for receiving the shoulder straps of a weight belt.
11. In a diving helmet, air inlet means for introducing air at the upper portion of the helmet, 20 said means comprising a sheath secured to and extending rearwardly from the top of the hel-

met, the top of the helmet having an opening therethrough adjacent the forward end of said sheath, means for attaching an air hose to said sheath, and means within said sheath formed of sound-deadening material provided with baffles whereby the course of the current of inflowing air is diverted, the baffles and the nature of the material of which the member is formed serving to decrease the velocity of the inflowing current of air and minimize noise.

80

12. A diving helmet having an air inlet opening in the wall thereof, means forming an inlet chamber for supplying air to said opening, an air inlet connection for introducing air into said chamber, and an air inlet member within said chamber and forming a passage of progressively increasing cross-section between said inlet connection and said inlet opening, said member being formed of rubber and including opposed baffles extending into said passage.
